UNITED STATES PATENT OFFICE.

WILLIAM THO. JOHNSON, OF STANDISH, MISSOURI.

SHOO-FLY ATTACHMENT FOR DOORS.

SPECIFICATION forming part of Letters Patent No. 655,242, dated August 7, 1900.

Application filed January 29, 1900. Serial No. 3,252. (No model.)

To all whom it may concern:

Be it known that I, WILLIAM THO. JOHNSON, a citizen of the United States, residing at Standish, Carroll county, Missouri, have invented a new and useful Shoo-Fly Attachment for Doors, of which the following is a specification.

My invention relates to a "shoo-fly" attachment for doors; and one object is to produce a device set in operation by the opening of the door whereby flies clinging to the door will be startled and instantly caused to fly off to such a distance that a person opening the door will have ample time to pass through the door-opening and the door to swing back and close before the flies can return and pass into the house.

A further object is to provide a device of the character mentioned which is of simple, cheap, and durable construction, which can be applied quickly and easily to any type of door, and which does not interfere in the slightest degree with the opening and closing of the door or the passage of a person through the door-opening.

With these objects in view and others as hereinafter appear the invention consists in certain novel and peculiar features of construction and combinations of parts, as will be hereinafter described and claimed, and in order that the invention may be fully understood I will proceed to describe it with reference to the accompanying drawings, in which—

Figure 1 represents a front view of a screen-door provided with a shoo-fly attachment embodying my invention. Fig. 2 is a top plan view of the same with the door partly open in full lines in one position and more widely opened and completely closed in dotted lines. Fig. 3 is a similar view showing the door open to a position at right angles with the plane of the door-frame. Fig. 4 is an enlarged perspective view showing the brush-carrying frame provided with a spring adapted to give an impetus to the collapse of the attachment, and thereby tend to facilitate the closing of the door. Fig. 5 is a view of the outer side of the upper portion of the door provided with a modified form of my device.

Referring to the drawings, where like ref-

erence - numerals designate corresponding parts, 1 designates the door-frame. 2 designates the door, preferably a screen-door, and provided with the customary spring-hinges 55 to effect its automatic closure.

The shoo-fly attachment is constructed as follows:

3 designates a bearing-clip secured to the door-frame and preferably located about as 60 shown in Fig. 1. 4 designates a similar clip also secured to the frame, preferably below the first-named clip.

5 designates a swinging frame, consisting of stiff wire bent to form the arm 6, terminating in a short vertical pivot 7, mounted in clip 3, and the brace-arm 8, terminating at the corresponding end in the similar pivot 9, mounted in the clip 4, said arm and brace-arm being connected at their opposite ends by 70 the upright portion 10, an eye or loop 11 being formed at the junction of said upright portion and arm and coincidently with the hinge-line of the door. The swinging frame extends as arranged in Fig. 1 across and flatly 75 against the upper face of the door, the lower or brace arm 8 by preference occupying a vertical plane slightly rearward of the arm 6 (see Fig. 2) to receive the direct thrust of the opening door, thereby relieving the brush 12, 80 pendent from the arm 6, from injurious wear or abrasion by contact with the door, this brush being constructed of fairly-stiff paper or any other substance which when violently agitated or jerked suddenly and swiftly 85

through the air will rattle and agitate the surrounding air to more effectually startle and dislodge the flies clinging in great number to the outside of the door. The brace-arm 8 not only stiffens and strengthens the 90 arm 6, but it also acts as a backing for the pendent brush, and consequently starts the same bodily outward instead of permitting it to trail slightly, like a kite-tail, from arm 6, as it otherwise would to some extent, and 95 therefore not make as much noise as desirable, and to insure that the brush shall not be injured by the door it may be desirable to bow the arm 6 outward slightly, as at 13, at the point opposite the free edge of the 100 door. (See Figs. 2 and 3.) A clip 14 is secured to the door and receives the depending pivot

16 of swinging link 15, said link being formed with a loop 17 at its opposite end pivoted to eye or loop 11.

The impact of the opening door against 5 brace-arm 8 swings or jerks the brush-carrying frame violently outward before the door has assumed the position shown in full lines, Fig. 2, and such movement of the frame is continued until it and the door attain the 10 positions indicated, respectively, by the letters *a* and *b*. From this position the continuous opening movement of the door through the medium of link 15 swings the brush-carrying frame inward, (see Fig. 3,) such movement 15 continuing until the door is completely opened and the brush is across the upper end of the door-opening, as will be readily understood. As the door is closed it at first through the medium of said link swings the brush-carrying frame outward until the latter attains position *a* and then reverses such movement and swings it inward until as the door attains its closed position the brush is again in position across the outer face and near the 20 upper end of the door, where it is again ready to startle the flies upon the reopening of the door.

Should the spring-hinges of the door become so ineffective as to be unreliable in re- 30 turning the door to its closed position, it may be desirable to mount a spring 18 on the upright portion 10 of the frame and secure its upper and lower ends to the link 15 and brace-arm 8, as shown, respectively, at 19 and 20, 35 (see Fig. 4,) which arrangement tends to effect the collapse of the frame—viz., the movement of the frame and link to approximately-parallel relation—and thereby facilitate the closing of the door by assisting the spring-hinges thereof to perform their proper function, as will be readily understood.

Although Figs. 1, 2, and 3 disclose the preferred embodiment of the invention, it may be desirable in some instances to use the simpler construction illustrated in Fig. 5, where it will be noticed the brace-arm 8 is dispensed with and the arm 6 provided with a substitute in the form of an arm 6^a, projecting into the path of movement of the door, that the 45 latter shall when opened swing the brush-carrying frame or arm 6 violently outward, as described. Either style could be employed in connection with a double door, one attachment for each door, but that shown in Fig. 55 5 would be preferable. To use the construction shown in Figs. 1, 2, and 3, it would of course have to be arranged above the door-opening.

From the above description it will be apparent that I have produced a shoo-fly attachment for doors possessing the features of advantage enumerated as desirable in the statement of invention, and it is to be understood that I reserve the right to make such 65 changes in the form, proportion, arrangement, or detail construction as properly fall within the spirit and scope of the appended claims.

Having thus described my invention, what I claim as new, and desire to secure by Letters Patent, is—

1. The combination with a door, of a frame pivoted to the door-frame adjacent to the free edge of the door, and embodying an arm in the path of the opening door so as to receive the thrust thereof, a brush carried by said pivoted frame, and a link pivotally connecting the door with said pivoted frame, substantially as described. 70 75

2. The combination with a door, of a frame comprising a substantially-horizontal arm 80 above the plane of the door and pivoted at its inner end to the door-frame, and a brace-arm, at the outer side and in the path of the opening door so as to receive the thrust thereof, pivoted at its inner end to the door-frame, 85 and united at its outer end to the outer end of said first-named arm, a brush carried by said pivoted frame, and a link pivotally connecting said pivoted frame with the door, substantially as described. 90

3. The combination with a door, of a frame comprising an arm adapted to swing in a plane above the door, and pivoted at its inner end to the door-frame, and a brace-arm arranged at the outer side and in the path of the door 95 below its upper edge and pivoted at its inner end to the door-frame vertically below the pivotal point of said first-named arm, and united to the outer end of said first-named arm, a link pivotally connecting the door with 100 the outer end of said pivoted frame, and a brush suspended from the first-named arm outward of said brace-arm, substantially as described. 100

4. The combination with a door, of a frame pivoted to the door-frame, and provided with an arm in the path of the door so as to receive the thrust of the latter as it opens, a brush carried thereby, a link pivotally connecting said pivoted frame with the door, and a spring 105 tending to cause said pivoted frame and link to assume an approximately-parallel relation, substantially as described. 110

5. The combination with a door, of a frame, consisting of a rod bent to form approximately-parallel arms pivoted at their inner ends to the door-frame, and connected at their outer ends by an upright portion and eye or loop, one of said arms lying in the path of the opening door so as to receive the thrust thereof, 115 a link pivotally connected to the door and to said eye or loop, and a brush depending from said pivoted frame, substantially as described. 120

6. The combination with a door, of a frame, 125 consisting of a rod bent to form approximately-parallel arms pivoted at their inner ends to the door-frame, and connected at their outer ends by an upright portion and eye or loop, one of said arms lying in the path of the opening door so as to receive the thrust thereof, a link pivotally connected to the door and to said eye or loop, a spring mounted on the upright portion, and secured at its ends to 130

said link and the lower arm of said pivoted frame, and a brush pendently attached to the upper arm of said pivoted frame, substantially as described.

5 7. The combination with a door, of a frame, consisting of a rod bent to form approximately-parallel arms pivoted at their inner ends to the door-frame, the lower arm occupying a plane nearer to the outer face of the door when closed than the upper to receive the thrust of the door in its opening move-

ment, said arms being connected at their outer ends by an upright portion and eye or loop, a link pivotally connected to the door and to said eye or loop, and a brush depending from said pivoted frame, substantially as described. 15

In testimony whereof I affix my signature in the presence of two witnesses.

WILLIAM THO. JOHNSON.
